UNITED STATES PATENT OFFICE.

JOHN DANKS, OF TROY, NEW YORK.

BURNER FOR PURIFYING GAS.

Specification of Letters Patent No. 32,124, dated April 23, 1861.

To all whom it may concern:

Be it known that I, JOHN DANKS, of Troy, in the county of Rensselaer and State of New York, have invented a new and useful 5 Improvement in Gas-Burners; and I do hereby declare that the following is a full, clear, and exact description of the same, reference being had to the accompanying drawing, forming part of this specification, said 10 drawing representing a central section of a burner with my improvement.

My invention consists in furnishing a gas burner with a chamber filled with hemp or flax saturated with nitric acid, such chamber 15 being so arranged that the gas on its way to the external orifice of the burner is caused to pass through the interstices between the fibers of the hemp or flax by which it is prevented blowing through the burner and passing 20 off unconsumed, and is so purified as to produce a very brilliant light.

A is the burner tip which may be of any known kind.

B is the chamber, made of brass, iron or 25 other metal, of spheroidal, cylindrical or other form, made with a female screw socket *a*, at its upper end, for the reception of the tip A, which screws into it, and with a female screw socket *b*, at the bottom similar to 30 that at the bottom of an ordinary burner. To provide for the insertion of the hemp or flax *c*, *c*, within it, the chamber B, is divided at the middle of its height into two parts which are screwed together at *d*, *d*. 35 The hemp or flax *c*, *c*, with which the said chamber is filled is in the fibrous condition to which it is brought by the breaking and

heckling or other processes; and after having been gathered up and well saturated with nitric acid is packed into the chamber 40 while still wet with the acid. The hemp or flax packing *c*, *c*, acts mechanically to break the pressure of the gas when excessive and so prevent any blowing through the burner without being consumed, and preserve a uniform 45 consumption, and a uniform light. The nitric acid with which the hemp is saturated acts chemically to purify the gas.

To avoid any corrosive effects of the acid, the burner may be made of, or lined with 50 porcelain or other anticorrosive substance. But the material of which the burner is composed forms no part of the present invention. When it becomes necessary to resupply the hemp with acid the burner is to 55 be removed from the gas pipe and the acid poured in through the aperture; or the parts of the chamber may be separated and a fresh supply of hemp also inserted.

I do not claim broadly the furnishing of 60 a gas burner with a chamber filled with fibrous material; but

What I claim as my invention, and desire to secure by Letters Patent, is:—

The employment as a filling for a chamber 65 B, applied in combination with a burner substantially as described, of hemp or flax saturated with nitric acid, as herein set forth.

JOHN DANKS.
